Lee W. Esterbrook

UNITED STATES PATENT OFFICE.

LEE W. ESTERBROOK, OF WASHINGTON, DISTRICT OF COLUMBIA.

SOUND-REPRODUCING INSTRUMENT.

Application filed June 17, 1924. Serial No. 720,635.

To all whom it may concern:

Be it known that I, LEE W. ESTERBROOK, a citizen of the United States, and resident of Washington, in the District of Columbia, have invented certain new and useful Improvements in Sound-Reproducing Instruments, of which the following is a specification.

My invention relates to improvements in reproducers for radio loud talkers or other sound reproducing devices, and it consists in the combinations, constructions and arrangements herein described and claimed:

An object of my invention is to provide a diaphragm for sound reproducing and recording instruments by means of which a clear, natural and loud tone is secured and in which disagreeable noises are eliminated.

A further object of my invention is to provide a device in which each sound is reproduced distinctly according to its tone value when in combination with numerous other sounds.

A further object of my invention is to use a combination of materials hitherto not used in a diaphragm for sound recording and reproducing instruments.

Other objects and advantages will appear in the following specification and drawings and the novel features of the invention will be pointed out in the appended claims.

In the accompanying drawings:

Fig. 1 is a plan view of one form of diaphragm.

Figs. 2, 3, 4, 5 and 6 are plan views of modified forms of this diaphragm.

Fig. 7 is a cross-section on the line *a—a* of Fig. 1.

Fig. 8 is a cross-section on the same line *a—a* of Fig. 1 showing corrugations used in place of strips. These corrugations separate the diaphragm into sections having different periods of vibration in a similar manner as the strips.

My invention herewith described consists of a diaphragm for use in sound recording and reproducing instruments of some suitable substance such as phenol condensation product or silicon steel to a face of which are attached short ribs or strips of a stiff but bendable material. The object of these strips is to divide the diaphragm into sections of various size and flexibility, each section having its own natural period of vibration.

The various sections will respond to impulses of their own frequency and com-

bine to reproduce the full natural tones impressed upon them without distortion or confusion.

In Fig. 1 is shown a form of diaphragm in which the strips *b—b* are narrow and of varied length and width. The group of these members is arranged in a general oblong form each being firmly held to one face of the diaphragm. In Fig. 2 is shown a diaphragm in which the strips are of nearly equal width, arranged in a circular form and connected by means of narrow strips from the same piece of material. Fig. 3 is a modified form of diaphragm in which the strips are all of different lengths connected by narrow parts of the same piece of material. Fig. 4 is a modified form of diaphragm in which narrow strips are arranged from the center outward in the form of a pyramid and inverted pyramid. Fig. 5 is a modified form of diaphragm in which the members are curved. Fig. 6 is a modified form of diaphragm in which the disk has five sides and a group of strips is arranged parallel with each side. In all of these diaphragms the strips are arranged to form graded scales, that is: The longest strip in each group lies next to one shorter than itself. The variance in length continues regularly in this manner from the longest strip in each group to the shortest in the same group so that the ends of the strips in each scale to a straight line or a curve as shown in the accompanying drawings.

There are two principal methods which can be used in the construction of a diaphragm intended to act in relation with a magnet or magnets. According to one method a disk is cut from a sheet of suitable magnetic material of proper size and shape to fit the housing of a loud talker unit. A number of strips of fibrous material impregnated with a phenol condensation product are cemented on a face of the disk as shown in Figure 1. I prefer to cut these strips $\frac{1}{16}$ of an inch wide except the center one which I make $\frac{1}{8}$ wide. For different effects I use other widths. I cut the strips from $\frac{1}{2}$ to $1\frac{1}{2}$ inches in length for a diaphragm of $2\frac{1}{8}$ inches in diameter, varying these lengths when different results are desired. This method may be used with all of the forms of diaphragms shown in the drawings and described in the specification.

When diaphragms are constructed according to Figs. 4, 5 and 6 they function better if

a magnet is supplied for each group of resilient material and members consisting of narrow strips of varying lengths and of different material from the disk arranged in groups to form graded scales closely attached thereto.

What I claim is:

1. A diaphragm for sound reproducing or recording instruments comprising a small sheet of resilient material and members consisting of flexible strips of varying length arranged at equal distances each from its nearest neighbor on one face of the diaphragm and closely attached thereto.
2. A diaphragm for sound reproducing or recording instrument comprising a small sheet of resilient, magnetic material and members consisting of strips of different material and varying area arranged in group form in such a manner that they form regularly graded scales closely attached thereto.
3. A diaphragm for sound reproducing or recording instruments comprising a disk of

25
narrow strips of varying lengths and of different material from the disk arranged in groups to form graded scales closely attached thereto.

4. A diaphragm for sound reproducing or recording instruments comprising a disk of resilient, magnetic material and members consisting of narrow strips of varying lengths arranged in the form of graded 30 scales closely attached thereto.

5. A diaphragm for sound reproducing or recording instruments comprising a disk of resilient, magnetic material and members consisting of attached strips of varying 35 lengths in group form so arranged that each group forms a regularly graded scale.

In testimony whereof I affix my signature.

LEE W. ESTERBROOK.
